UNITED STATES PATENT OFFICE

170,120

CRIBBAGE BOARD

Siegfried Gordon Isserstedt, Toronto, Ontario,
Canada

Application January 9, 1952, Serial No. 17,969
In Canada November 24, 1951

Term of patent 14 years

(Cl. D34—5)

To all whom it may concern:

Be it known that I, Siegfried Gordon Isserstedt, a citizen of the Dominion of Canada, resident of the city of Toronto, county of York, Province of Ontario, Canada, have invented a new, original, and ornamental Design for a Cribbage Board, of which the following is a specification, reference being had to the accompanying drawing, forming a part thereof.

Figure 1 is a plan view of a cribbage board, showing my new design; and

Figure 2 is a side view thereof.

I claim:

The ornamental design for a cribbage board, substantially as shown.

SIEGFRIED GORDON ISSERSTEDT.
